CLAIM

(57) The ornamental design for an avionics display screen with graphical user interface, as shown and described.

DESCRIPTION

FIG. 1 is a front view of the avionics display screen with graphical user interface, showing our new design; and, FIG. 2 is another front view thereof.

The broken line perimeter of the design representing the display screen and all features including lines, words and numbers drawn in broken lines within this perimeter form no part of the claimed design.
